UNITED STATES PATENT OFFICE.

HUGO LOEWENBACH, OF MILWAUKEE, WISCONSIN.

TOILET-PAPER CABINET.

SPECIFICATION forming part of Letters Patent No. 678,434, dated July 16, 1901.

Application filed June 20, 1899. Serial No. 721,190. (No model.)

To all whom it may concern:

Be it known that I, HUGO LOEWENBACH, a citizen of the United States, residing at Milwaukee, in the county of Milwaukee and 5 State of Wisconsin, have invented new and useful Improvements in Toilet-Paper Cabinets, of which the following is a specification.

My invention relates to improvements in toilet-paper cabinets.

10 The objects of my invention are, first, to provide a form of cabinet in which the paper may be supported against a solid or rigid back plate, all devices for pressing the paper forwardly to the feeding mechanism being 15 dispensed with, and, second, to provide a form of cabinet which can be manufactured at such small cost that it can be sold with each individual package of paper and destroyed when the package is exhausted.

20 In the following description reference is had to the accompanying drawings, in which—

Figure 1 is a perspective view of my invention; Fig. 2, a sectional view drawn on line $\alpha\alpha$ of Fig. 1. Fig. 3 is a rear view of the 25 friction-plate.

Like parts are identified by the same reference-letters throughout the several views.

The inclosing cabinet or case A is provided with a flexible front B and a suspension-tongue D, the latter being preferably perforated or slotted, as shown at d , for the insertion of a binding-screw C. The screw C is preferably provided with a washer E, between which and the point of support the 35 tongue D may be clamped by tightening the screw.

A frictional paper-discharging device, preferably in the form of a plate F and provided on its bearing-surface with sandpaper G, is 40 suspended in the interior of the cabinet by elastic cords H, which are preferably extended transversely of the cabinet and secured to the side walls or to the front B near the side walls, so that the friction-plate F may be 45 easily moved both inwardly and downwardly in the rear of the front wall B. The front B of the cabinet is provided with a slot I, through which a friction-plate handle J projects in a position to be readily grasped by the user.

50 The package of paper K is inserted in the cabinet in the rear of the plate F and sus-

pended therein by a binding-wire L, which is secured to the back wall of the cabinet. The device is operated by pressing the friction-plate F inwardly against the face of the pack- 55 age and then downwardly, when the friction of the plate pulls the front sheet away from the binding and causes it to fall to the lower end of the cabinet. The lower end of the cabinet is open, but stops M are provided to 60 engage and detain the released sheets until taken by the user.

It will be observed that as the front of the cabinet is flexible and the plate F is also free to move inwardly from the front the friction 65 device can be readily pushed against the paper and operated to discharge the sheets successively until the package is wholly exhausted. The front of the cabinet is of course supported entirely by the side walls, being 70 unattached to either of the end walls, so that it can be readily pushed inwardly to the position illustrated by dotted lines in Fig. 2. The handle J is preferably also made flexible or otherwise arranged, so that it can be 75 folded for convenience in making shipments.

It will be understood that the entire cabinet, with the friction-plate and handle therefor, may be made of cardboard, the only other material used in the construction of the device being the suspensory devices of the plate F and the sandpaper or other frictional substance on the bearing-surface of the plate F. The plate F is preferably suspended by means of rubber bands or cords H, which can be conveniently secured at the respective ends by engaging the same in a loop formed by a cardboard strip N, which is then pasted together and to the interior surface of the cabinet. 85

It is obvious that with the described construction the cabinets can be produced at an extremely low cost, so that I am enabled to provide a separate cabinet for each package of paper. The construction shown and described will therefore be found sufficiently durable for the purpose. 95

Having thus described my invention, what I claim as new, and desire to secure by Letters Patent, is—

1. A toilet-paper cabinet, comprising an in- 100 closing cabinet or case, provided with a discharge-opening; a yielding front wall or cover,

provided with a slot; and a paper-discharging device suspended by an elastic support in the rear of said slot.

2. A toilet-paper cabinet, comprising an in-closing cabinet or case, provided with a discharge-opening and having a slot in the front wall or cover; and a paper-discharging device provided with a folding handle and suspended by flexible connection in the rear of said slot, and adapted to be moved inwardly and downwardly under pressure applied through said slot.

3. A toilet-paper cabinet, comprising an in-closing cabinet or case, provided with a discharge-opening, and having a yielding front wall or cover provided with a slot therein; and a paper-discharging device suspended in the rear of said slot by flexible connections and adapted to move inwardly and downwardly from the front wall.

4. A toilet-paper cabinet, comprising an in-closing cabinet or case, provided with a discharge-opening, and having a yielding front

wall or cover provided with a slot therein; and a paper-discharging device suspended in the rear of said slot by flexible connections and adapted to move inwardly and downwardly from the front wall; and a folding handle secured to said paper-discharging device, and adapted to project through said slot.

5. A toilet-paper cabinet, comprising an in-closing cabinet or case, provided with a discharge-opening and having a yielding front wall or cover, and a paper-discharging device suspended by flexible connections within the cabinet, and adapted to move inwardly and toward the discharge-opening, in combination with a toilet-paper package secured to the rear wall of said cabinet.

In testimony whereof I have hereunto set my hand this 17th day of June, 1899.

HUGO LOEWENBACH.
